UNITED STATES PATENT OFFICE

CLINTON L. WALKER, OF PIEDMONT, CALIFORNIA

PISTON GIB

Application filed August 30, 1930. Serial No. 478,884.

This invention relates to pistons for use in pumps, engines, and the like, and more particularly to the means for connecting the pistons to the crank shaft in that type of engine employing the Scotch yoke mechanism such for instance, as is particularly shown in my patent entitled "Air pump", #1,263,166, April 16, 1918. This type of pump or engine consists of a straight shaft to which is attached one or more eccentrics and surrounding each eccentric is a rectangular frame, said frames being fitted to the eccentric and being formed of the right types of metal to permit of high rotational speed as between these parts. This rectangular frame has flat, smooth and parallel surfaces on two or four sides according to whether two or four cylinders are operated from each eccentric. This frame in turn, bears against a flat surface on a gib, mounted in the piston proper, and it is the object of this invention to improve the bearing and lubricating conditions as between the rectangular frame and the bearing gib. This is accomplished in this invention by increasing the length of the contacting surfaces between the frame and the gib to such an extent that the length of the gib exceeds the diameter of the bore of the cylinder.

One form which my invention may assume is exemplified in the following description and illustrated by way of example in the accompanying drawings, in which:

Fig. 1 is a side elevation of a piston showing the piston and a side view of the gib together with a fragment of the rods connecting the pairs of pistons which are employed in this type of opposed motor.

Fig. 2 is also a side elevation of the piston, but shows an end view of the bearing gib.

Fig. 3 is a perspective view of the gib.

Fig. 4 is a diagram illustrating the general type of engine or pump to which this construction is attached.

Similar numerals of reference indicate corresponding parts in the several views of the accompanying drawings.

1 illustrates the skirt of the piston having the usual ring and head section; 2 illustrates the back side of the gib which comes in con-

tact with a seat of corresponding contour in the piston and corresponds to the wrist pin used in the conventional type of connecting rod engine. 3 is a channel member attached rigidly to 2, but is greater in length than 2 for the purpose of increasing the bearing area of the inner face of the channel and to reduce the amount of oil thrown into the cylinder at the end of the stroke. 4 are connecting rods, four in number for each pair of pistons operating off from each pair of parallel sides of the rectangular frame.

It has been found from experience that unless the length of the bearing surface between the frame and the gib exceeds the bore of the cylinder that the oil and the bearing metal particularly adjacent the ends of the gib will break down, and that an excess of oil will be thrown into the cylinder at the outer end of the stroke, but where the length of the gib is increased greater than the bore of the cylinder, the condition will be materially improved.

While certain features of the present invention are more or less specifically illustrated, I wish it understood that various changes in form and proportion may be resorted to within the scope of the appended claims. I similarly wish it understood that the materials and finish of the several parts employed may be such as the experience and judgment of the manufacturer may dictate or various uses demand.

Having thus described my invention, what I claim and desire to secure by Letters Patent is:

1. Means for transmitting power between a rigidly connected pair of pistons and a shaft which consists of an eccentric mounted on said shaft, a rectangular frame with a circular opening fitted to said eccentric, said frame having oppositely disposed parallel bearing surfaces slidably fitted to bearing gibs, said gibs being fitted into corresponding seats in the pistons, said gibs having a length greater than the bore of the cylinders that the pistons fit in.

2. Means for transmitting power between a rigidly connected pair of pistons and a shaft which consists of an eccentric mounted

on said shaft, a rectangular frame with a circular opening fitted to said eccentric, said frame having oppositely disposed parallel bearing surfaces slidably fitted to bearing gibs, said gibs being fitted into corresponding seats in the pistons, said gibs having a channel section on its bearing face to guide the said rectangular frames.

3. Means for transmitting power between

10 a rigidly connected pair of pistons and a shaft which consists of an eccentric mounted on said shaft, a rectangular frame with a circular opening fitted to said eccentric, said frame having oppositely disposed parallel bearing surfaces slidably fitted to bearing gibs, said gibs being fitted into corresponding seats in the pistons, said gibs consisting of a segment of a tube welded to a channel member.

20 4. Means for transmitting power between a rigidly connected pair of pistons and a shaft which consists of an eccentric mounted on said shaft, a rectangular frame with a circular opening fitted to said eccentric, said frame having oppositely disposed parallel bearing surfaces slidably fitted to bearing gibs, said gibs being fitted into corresponding seats in the pistons, said gibs consisting of a segment of a tube with segmental abutments

30 on the convex surface, said tube segment being rigidly attached to a channel member.

5. Means for transmitting power between a rigidly connected pair of pistons and a shaft which consists of an eccentric mounted

35 on said shaft, a rectangular frame with a circular opening fitted to said eccentric, said frame having oppositely disposed parallel bearing surfaces slidably fitted to bearing gibs, said gibs being fitted into corresponding seats in the pistons, said gibs having a segmental form at the back and a channel form at the front, said channel section being faced with babbitt on its wearing surfaces.
